UNITED STATES PATENT OFFICE

152,472

DESIGN FOR A BIRD HOUSE

Bertil E. Hawkinson, Duluth, Minn.

Application July 24, 1947, Serial No. 140,490

Term of patent 7 years

(Cl. D31—2)

To all whom it may concern:

Be it known that I, Bertil E. Hawkinson, a citizen of the United States, residing at Duluth, in the county of St. Louis and State of Minnesota, have invented a new, original, and ornamental Design for a Bird House, of which the following is a specification, reference being had to the accompanying drawing, forming part thereof.

Figure 1 is a side elevation of a bird house, showing my new design, and

Figure 2 is a front elevation thereof.

I claim:

The ornamental design for a bird house, as shown.

BERTIL E. HAWKINSON.
